US0D1069921S

(12) United States Design Patent (10) Patent No.: US D1,069,921 S
(45) Date of Patent: * Apr. 8, 2025

(54) GAMING MACHINE

(71) Applicant: Aristocrat Technologies Australia Pty Limited, North Ryde (AU)

(72) Inventors: Rena Schoonmaker, Las Vegas, NV (US); Dominic DeMarco, Round Rock, TX (US)

(73) Assignee: Aristocrat Technologies Australia Pty Limited, North Ryde (AU)

() Term: 15 Years

(21) Appl. No.: 29/893,258

(22) Filed: May 26, 2023

Related U.S. Application Data

(60) Continuation of application No. 29/795,281, filed on Jun. 17, 2021, now Pat. No. Des. 990,575, which is a continuation of application No. 29/722,154, filed on Jan. 27, 2020, now Pat. No. Des. 926,259, which is a continuation of application No. 29/680,138, filed on Feb. 13, 2019, now Pat. No. Des. 888,159, which is a division of application No. 29/619,823, filed on Oct. 2, 2017, now Pat. No. Des. 846,649.

(57) CLAIM

The ornamental design for a gaming machine, as shown and described.

DESCRIPTION

FIG. 1 is a front perspective view of a gaming machine showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the drawings illustrate portions of the gaming machine that form no part of the claimed design.
